UNITED STATES PATENT OFFICE.

WILLIAM C. MARTINEAU AND CLARENCE R. MARTINEAU, OF ALBANY, NEW YORK.

LOCKING DEVICE.

1,149,205.

Specification of Letters Patent. Patented Aug. 10, 1915.

Application filed September 21, 1914. Serial No. 362,791.

To all whom it may concern:

Be it known that we, WILLIAM C. MARTINEAU and CLARENCE R. MARTINEAU, both citizens of the United States, and residents 5 of the city and county of Albany, New York, have invented certain new and useful Improvements in Locking Devices, of which the following is a specification.

Our invention relates to hasp and staple 10 devices such as are used chiefly on sliding doors. They are particularly useful on car doors.

The object of our invention is to produce such a device which shall be adapted to 15 doors sliding either to the right or left of their closed position, which shall be securable to the door and casing, so as to be practicably irremovable from without.

Further objects of our invention will appear 20 in this specification and be pointed out in the claims.

In the drawings Figure 1 is a partial elevation of a casing and door provided with our invention, Fig. 2 is a horizontal section 25 through the plane 2—2, Fig. 1; Figs. 3 and 4 are enlarged perspective views of parts of the staple device; Figs. 5 and 6, 7 and 8, 9 and 10 are views similar to Figs. 3 and 4 but showing modifications, Fig. 11 30 is a reversed elevation of the hasp portion of the device shown in Fig. 1. Figs. 12 and 13 are partial elevations of details of the device.

In the particular embodiment of our invention illustrated in Figs. 1, 2, 3, 4 and 11 35 of the drawing, 21 designates the side or body of a car or other structure, 22 is a door sliding thereon by means of any well known or desired form of hanger, not shown; 23 40 is a vertical post on casing 21 against which door 22 strikes, 24 is a hasp plate formed with a widened head 25, flange 26, boss 27, in which is a slot 28 having a widened middle portion 29, and provided with integral bolts 30 threaded for engagement 45 with nuts 31 on the inner side of the door. 32 is a hasp consisting of a plate portion 33 formed with apertures 34, shown as two in number, a curved shank 35 and an enlarged 50 button head 36, 37 is a striker plate formed with an aperture 38, a laterally projecting guide member 39, rearwardly projecting flanges 40, a laterally projecting flange 41 at the rear of one of flanges 40, and integral 55 bolts 42 projecting rearwardly from plates 37 and lug or flange 41. 43 is a detachable

staple plate provided with apertures 44 corresponding in number and position to bolts 42 on plate 37, and apertured staple 45, pivoted depending lugs 46 having outwardly 60 projecting members 47 each formed with an aperture 48, laterally projecting thumb pieces 49, stop 50 and rearwardly extending integral bolt 51.

The operation of the device is as follows: 65 Door 22 being slid to its closed position, hasp 32 is passed over staple 45, lugs 46 being first raised to their horizontal position, shown in dotted lines Fig. 4. Lugs 46 are then allowed to drop to their normal position when apertures 48 in lugs 47 will 70 register with a similar aperture in staple 45, so that the shackle of a seal or the hook portion of a padlock may be passed through all three thereby securely sealing the car. It 75 will be noted that the integral bolts 30 on plate 24 pass through the door and are secured by nuts 31 on its inner side, so that there is no means of removing plate 24 when door 22 is closed. In door 22 is an aperture 80 52 adapted to be covered by plate 53 and to register with the slotted portion of plate 24, which permits hasp 32 to be removed from or replaced in slot 28 without removing plate 24 from the car. This is advantageous 85 because hasp 32, usually made of malleable iron, projects beyond plate 24 and is liable to be broken with the rough treatment to which freight cars are subjected. A plate 90 53 is screwed to the inner side of end 25, so as to cover the rear face of boss 27 and prevent the accidental removal of hasp 32. Hasp 32 swings vertically and horizontally 95 in the middle portion 29 of slot 28. It is obvious that either of its apertures 34 may be engaged over staple 45, in one case, as shown, the door 22 in its tightly closed position; or if the outer aperture 34 is used, the door is held slightly open. The guide member 39 on striker 37 serves to guide the door 100 to its closed position and to reinforce it against being forced outward. As shown in the drawing, door 22 slides to the left to gain its closed position, and this is the ordinary construction. 105

Staple plate 43 is engaged with striker 37 by sliding its apertures 44 over the two rearwardly disposed bolts 42 so as to bring the face of plate 43 against the rear face of striker portions 37, and so that plate 43 110 closes aperture 38 with its parts 45—50 projecting therebeyond. It will be noted that

striker 37 and plate 43 are both provided with integral bolts which pass through the body of the car and are threaded for engagement with nuts therein, staple plate 43 being additionally protected from removal from without by its ends being covered by striker plates 37.

Where a car door is closed by sliding it to the right, it is obvious that all the parts of our device except plate 43 are inverted, so that guide 39 serves the same function as before, although it is below instead of above the hasp portion. It is of course clear that plate 43 is adapted to engage with striker 37 when either in the position shown or in an inverted position.

The striker and hasp device shown respectively in Figs. 5 and 6 are similar to those already described, except that bolts 42 and 51 are omitted, their place being supplied by bolt holes 421 and 511 respectively, so that ordinary bolts or screws may be used.

In the corresponding parts shown in Figs. 7 and 8, striker 54 is provided as before with guide 39, flanges 40 and 41 and bolts 42. Beneath its head portion 55 is a plate 56 provided with apertures 57 and a staple 58, having an aperture 59, see Fig. 7. The plate 60, shown in Fig. 8, is provided with rearwardly projecting bolt 61 and with an aperture 62 corresponding in size and position to staple 58, plate 60 being adapted to cover plate 56 and being provided with lugs 46 as shown in Fig. 4. It is obvious that both striker and plate may be secured to the car body as before, and that their functions are the same as that already described.

The striker and plate of Figs. 9 and 10 are like those of Figs. 7 and 8, except that bolts 42 and 61 are omitted and bolt holes 421 and 611 substituted therefor. It will, of course, be understood, that the omission of the integral bolts is a sacrifice of part of the advantages of our invention for the sake of economy.

Fig. 12 shows the rear end of a bolt 63, which may be one of the bolts on plate 24 or on one of the strikers or hasp plates shown. It is shown as passed through wall 64 which may be either a door or body of a car. At its inner end, bolt 63 is provided with a transverse aperture 65 so positioned that its rear portion extends beyond the inner face of wall 64. A wedge 66 is passed through aperture 65, driven as tight as possible and secured in place by a screw 67 passing through a small aperture 68 in the end of the wedge. It is obvious that this method of securing the bolt is an efficient, and in some cases, an economical substitute for the threaded end and nut above described.

Fig. 13 shows a somewhat similar device

in which a number of bolts, as for instance, bolts 30 shown in Fig. 2, may be secured. In each bolt 70 is cut a transverse aperture 65 as before, a single strap 71 passing through all these apertures and being secured by screws 72 on the inner face of door 22.

It will be understood that various mechanical changes, other than those shown, 70 may be made in our device without departing from the spirit of the invention; also that parts of the device may be employed without the others.

Our invention is in some sense an improvement on an application filed May 15, 1914; Serial Number 838745 by ourselves and A. Benjamin Appler; in that it provides, in some forms of construction, integral bolts so that the exterior surfaces of the parts are solid and unbroken; in that it is adapted to right or left running doors; in that it provides for the renewal of a broken hasp without the removal of the hasp fixture and in that it provides in Figs. 12 and 13 85 for a novel method of securing the bolts in place.

What we claim is:

1. In a locking device adapted to be secured on a door having an aperture near its edge, a hasp plate securable to said door and having an apertured portion covering such door aperture, a hasp portion adapted to pass through said plate aperture except for a head at its pivoted end; and detachable 95 means in said door aperture for preventing the withdrawal of said hasp through said plate aperture.

2. In a locking device adapted to be secured to a door having an aperture near its 100 edge, a hasp plate securable to said door and having an apertured portion covering such door aperture; a hasp portion adapted to pass through said plate aperture, except for a head at its pivoted end; and detachable 105 means secured to the inner face of said plate and within said door aperture for preventing the withdrawal of said hasp through said plate aperture.

3. In a locking device for a sliding door, 110 a striker portion provided with means for securing it to the door casing, with either of its ends uppermost, a staple plate adapted to be engaged with said striker portion in either of its positions, and without inversion 115 of said staple plate, whereby said locking device may be used on doors movable in either direction from their closed position.

WILLIAM C. MARTINEAU.
